PORTABLE POWER-OPERATED SABRE SAW

Michael P. Ballone, Baltimore, and Roderick F. Bunyea
and Russell A. Fritts, Towson, Md., assignors to The
Black and Decker Manufacturing Company, Towson,
Md., a corporation of Maryland

Filed Oct. 1, 1968, Ser. No. 13,797

Term of patent 14 years

Int. Cl. D8—02

U.S. Cl. D8—64

FIG. 1

FIG. 2

FIG. 3FIG. 4FIG. 5FIG. 1 is a side elevational view of the portable power-operated sabre saw, showing our new design;

FIG. 2 is a top plan view of the saw of FIG. 1;

FIG. 3 is a bottom plan view of the saw of FIG. 1;

FIG. 4 is a front elevational view of the saw of FIG. 1; and

FIG. 5 is a rear elevational view of the saw of FIG. 1.

The dominant features of our design reside in the portions shown in full lines.

We claim:

The ornamental design of a portable power-operated sabre saw, as shown and described.
